UNITED STATES PATENT OFFICE.

HERBERT J. BRAGDON, OF CHICAGO, ILLINOIS, ASSIGNOR TO GEORGE HEINLEIN, OF CHICAGO, ILLINOIS.

WIRE SHAPING AND FORMING MACHINE.

No. 884,633.

Specification of Letters Patent.

Patented April 14, 1908.

Application filed June 21, 1907. Serial No. 380,168.

To all whom it may concern:

Be it known that I, HERBERT J. BRAGDON, a citizen of the United States, residing at Chicago, in the county of Cook and State of Illinois, have invented a new and useful Wire Shaping and Forming Machine, of which the following is a specification.

The wire shaping and forming machine that is the subject of my invention has for its object the forming and shaping of pieces of wire into various objects adapted to be made of wire.

This specification particularly describes the machine as adapted to shape and form small wire tag holders, but by varying the shapes of the die and plungers, hereinafter referred to, and by varying the adjustments of the different parts of the machine, wire rings or wire clips or any other object adapted to be formed by bending wire may be made, as will be readily understood upon consideration of the mechanism hereinafter described.

In the accompanying drawings, Figure 1 is a plan view of the machine as seen from above; Fig. 2 is a section on the line 2—2 of Fig. 1, showing a side view of the forming die and the rotating plungers; Fig. 3 is a section on the line 3—3 of Fig. 1, showing a side view of the apparatus for cutting the wire into the required lengths; Fig. 4 is a plan view of the forming die; Fig. 5 is a front view of the forming die; Fig. 6 is a section on the line 6—6 of Fig. 4; Fig. 7 is a perspective view of the cam which is attached to the die for throwing off the completed article; Fig. 8 is a section on the line 8—8 of Fig. 1, showing the cutter bearing mechanism and the means of attaching said mechanism to the driving shaft; Fig. 9 is a section taken on the line 9—9 of Fig. 8; Fig. 10 is a side view, partly in section, of one of the forming plungers, showing the mechanism for throwing the completed article off the plunger; Fig. 11 is a view of the forming plungers taken from the front, showing the same mechanism for throwing off the completed article; Fig. 12 is a detailed view of the reciprocating pin which passes through the outer end of each plunger and throws off the completed object; and Fig. 13 is a view in perspective of a tag fastener as formed by this machine.

Similar numerals refer to similar parts throughout the several views.

It seems best to explain in general terms

the structure and operation of the machine before entering into a detailed explanation referring to the figures on the drawings.

The entire apparatus will take up very little space. The frame of the machine is made of suitable metal and is supported on legs, made of suitable metal or other material, which bring the mechanism up to a convenient height from the floor for the purposes of operation.

In the front of and at one side of the machine may be placed a drum or spool on which the wire which is to be cut and formed is wound. This drum or spool is not shown in the drawing but would be placed at the lower left-hand corner of the machine shown in Fig. 1 of the drawings. The end of the wire is then passed between a pair of feed rollers, and the machine is ready for operation.

All the power for operating the machine is applied to a pulley which is attached to a driving shaft passing through the center of the frame of the machine. The frame of the machine and the various parts may be of different sizes for the purpose of making articles of different sizes, but in the machine described in this specification, which is, as stated, adapted for the formation of wire tag holders, the frame of the machine is only about twenty-three inches by twenty-four inches.

After the end of the wire has been inserted between the feed rollers and the power turned on, the feed rollers feed the wire into the machine in a direction parallel with the driving shaft. After the wire has been fed into the upper inner edge of the forming die, one of the four cutters which revolve around the driving shaft immediately outside of the upper outer edge of the forming die, cuts the wire against a stationary cutting edge, leaving within the forming die at its upper edge a section of wire just equal in length to the entire length of the completed article. Just as this section of wire is cut by the cutter, one of the four plungers, which also rotate around the power shaft, descends upon the section of wire which has been cut off and forces it downward through the forming die, which is stationary, and occupies the space of about a quarter of a circle which has the center of the power shaft as its center. This forming die at its upper edge is straight but the outer

edges of it are gradually formed upwards and then inwards towards each other so that at its under end it is so shaped that as the wire is forced through it by the plunger, the outer 5 ends of the wire are bent first upwards and then inwards towards each other.

Near the lower end of the forming die a cam is attached to it which extends perpendicularly above it and has its upper end bent 10 at right angles in over the forming die. On the plunger is pivoted an arm which projects out above it and carries pivoted to it another arm at right angles to the first one extending toward the outer edge of the plunger. This 15 arm in turn carries a pin which extends through an opening in the end of the plunger and carries a cam on its end. As the plunger presses the wire through the die the aforesaid cam attached to the die catches the arm pivoted to the plunger and depresses it, thereby depressing the pin which projects through the edge of the plunger and throws off the completed article into a sack which may be placed to receive it. As soon as the 20 plunger passes the said cam attached to the die, the arm pivoted to said plunger is released and is thrown into its former position by a spring which passes around the pin which extends through the end of the plunger. 25

30 While the one section of wire has been so shaped in the die by one of the plungers, the uncut wire has been fed in until another section is in place at the upper edge of the die, when it in turn is cut off by another of the 35 cutters and is carried through the die by another plunger. On the machine shown in the drawings and described in this specification there are four cutters and four plungers.

Having now described the general method 40 of operation of the machine, I will enter upon a more particular description of the various details, referring to the drawings and the numerals thereon indicating the specific parts of the machine.

45 1 is the upper of the two guide rollers, (the under one of which is grooved for better feeding the wire) through which the wire is fed into the machine from the spool or drum (not shown).

50 2 and 3 are the gears by which the roller 1 and its counterpart are driven. The gear 3 is attached to and rotates with the main driving shaft 4, which is driven by a belt applied to the pulley 5.

55 6 is a pipe through which the wire is fed from the rollers 1. This pipe is bolted to the frame of the machine as indicated at 7.

60 8 is the stationary cutter-bar, which is bolted by the bolt 9 to a slot 10 in the frame of the machine, thus being adjustable on said frame.

65 11 are the four rotating cutters which are sunk into four openings prepared for them on the wheel 12, to which is screwed the plate 13 by the screws 14. This wheel 12 is held

rigidly attached to the driving shaft 4 by the bolt 15 and the feather 16. The rotating cutters 11 are held in place by the bolts 18, and when the bolts 18 are loosened, the rotating cutters 11 may be removed from the 70 openings in which they are placed, and may then be adjusted vertically by means of the bolts 17. The rotating cutters are also capable of adjustment around the driving shaft by means of the bolts 19 which fit in the 75 slots 20; this enables the rotating cutters to be adjusted forwards or backwards so as to adapt the cutting of the wire to the operation of the forming plungers, hereafter described.

The stationary cutter-bar 8 has bolted on it on its upper side a guide bar 21, for guiding the wire into the guides 29 at the upper end of the forming die. As the wire feeds out of the tube 6 and through the cutter it passes under the guide 29, which is secured at the head of the forming die 28. This guide 29 is bolted to the frame of the machine by the bolts 27 and the bolt 25, the latter being adjustable in the slot 26. The forming die 28 90 is bolted to the machine by the bolts 22, which are adjustable in the slot 23.

The forming die 28, when attached to the frame of the machine by the bolts 22, extends directly under the wheel which carries 95 the forming plungers; and this forming die occupies about the space of a quarter of a circle, said circle having for its center the center of the driving shaft of the machine. At its head the forming die presents a 100 straight surface, but both outer edges of it, beginning shortly below its head, are gradually bent upwards and inwards as shown at the points indicated by the numerals 30. This bending may be varied as it is desired 105 to vary the shape into which the wire is to be bent, without departing from the spirit of my invention. In the accompanying drawings the die is formed so as to properly bend the wire into the shape of the tag fastener 31. 110

The wheel 32 which carries the forming plungers is fastened to the driving shaft in the same manner as is the wheel 12, which carries the rotating cutters 11. The bolt 33 corresponds to the bolt 15. The bolts 34 115 correspond to the bolts 19 and permit of the rotary adjustment of the forming plungers in the same manner as the rotary adjustment of the rotating cutters, and the bolts 35 correspond to the bolts 18 and permit of the 120 vertical adjustment of the forming plungers in the same manner as the vertical adjustment of the rotating cutters.

The forming plungers, on the surface which comes in contact with the wire, carry the 125 rigid projections 36 and 37, which may also be made of such size and of such shape as may be necessary to fit in the recesses formed by the bent upper edges of the forming die. In the drawings the projection 36 is larger than 130

the projection 37 because the recess formed on the side of the forming die through which the projection 36 passes is larger than the recess formed on the side through which the 5 projection 37 passes, as in the tag fastener shown the bend at one end is wider than the bend at the other.

As the driving shaft revolves carrying the wheel which in turn carries the forming 10 plungers 33^a, the plunger comes in contact with the cut section of wire at the head of the forming die and carries it down through the forming die, the projection 36 passing along and through the recess 38 in the forming die 15 and the projection 37 passing along and through the recess 39 in the forming die, thus the ends of the section of wire are bent up and around the projections 36 and 37 toward each other and the completed article, 20 as shown in Fig. 13, is formed. As soon as the completed article is formed it is thrown off the forming plunger by the mechanism hereinafter described, and in the meanwhile 25 the next forming plunger has made another article, and so on.

On each of the forming plungers is pivoted an arm 40 which bears a roller 41. To this arm is also pivoted another arm 42, extending at right angles from the first arm and 30 toward the head of the forming plunger. The arm 42 comes in contact with the reciprocating pin 43 which extends through the head of the forming plunger, and carries on its end the lug 44, which fits in a recess on 35 the head of the forming plunger between the projections 36 and 37. Around the reciprocating pin 43 is fastened the spiral spring 45. To the forming die, at the point where the bending of the wire is completed, is 40 bolted, by the bolt 46, the cam 47, which bears the lug 48. As the forming plunger descends, the roller 41 strikes the lug 48, whereby the arm 42 is forced downward and the reciprocating pin 43 is forced downward 45 throwing the lug 44 out between the projections 36 and 37 and ejecting the completed article from the head of the forming plunger. As the plunger passes the cam 47 and the roller 41 is released from contact with the 50 lug 48, the spiral spring 45 throws the ejecting mechanism into its original position, and the arm 40 is prevented from springing too far in the opposite direction by the stop 51. The wheel 49 is a fly-wheel at the other end 55 of the driving shaft.

The lubrication of the die and forming plungers is most effectively done by allowing oil to drip onto the wire, either through holes, not shown in the drawings, cut through the 60 upper side of the tube 6, or at the end of said tube. Another possible method of lubrication is indicated by the recesses 50 shown in the drawings as formed at the head of the forming die, into which oil may be allowed 65 to drip.

Having now described my invention, what I claim is new, and desire to secure by Letters Patent is:

1. In a machine for shaping wire, the combination of mechanism for feeding the wire, mechanism for cutting the wire, and mechanism for shaping the wire consisting of one or more rotating forming plungers and a forming die through which said plunger carries or said plungers carry the wire, substantially as described. 70

2. In a machine for shaping wire, the combination of mechanism for feeding the wire, mechanism for cutting the wire, and mechanism for shaping the wire consisting of one or more rotating forming plungers, a forming die through which said plunger carries or said plungers carry the wire, and mechanism for ejecting the completed article, substantially as described. 75

3. In a machine for shaping wire, the combination of mechanism for feeding the wire, mechanism for cutting the wire and mechanism for shaping the wire consisting of one or more rotating forming plungers, adjustable vertically, and a forming die through which said plunger carries or said plungers carry the wire, substantially as described. 80

4. In a machine for shaping wire, the combination of mechanism for feeding the wire, mechanism for cutting the wire, mechanism for shaping the wire consisting of one or more rotating forming plungers, adjustable vertically, and a forming die through which said plunger carries or said plungers carry the wire, and mechanism for ejecting the completed article, substantially as described. 85

5. In a machine for shaping wire, the combination of mechanism for feeding the wire, mechanism for cutting the wire, and mechanism for shaping the wire consisting of one or more rotating forming plungers which are adapted for both vertical and rotary adjustment, and a forming die through which said plunger carries or said plungers carry the wire, substantially as described. 90

6. In a machine for shaping wire, the combination of mechanism for feeding the wire, mechanism for cutting the wire, mechanism for shaping the wire, consisting of one or more rotating forming plungers adapted for both vertical and rotary adjustment, a forming die through which said plunger carries or said plungers carry the wire, and mechanism for ejecting the completed article, substantially as described. 95

7. In a machine for shaping wire, the combination of mechanism for feeding the wire, mechanism for cutting the wire, and mechanism for shaping the wire consisting of one or more rotating forming plungers, and a forming die through which said plunger carries or said plungers carry the wire, the surface of said die at its upper edge being straight and from that point having gradually formed 100

on it a recess or recesses, into which the head of said plunger is or the heads of said plungers are adapted to fit, and between which and the head of said plunger or the heads of 5 said plungers, the wire may be bent, substantially as described.

8. In a machine for shaping wire, the combination of mechanism for feeding the wire, mechanism for cutting the wire and mechanism for shaping the wire consisting of one or more rotating forming plungers, and a forming die through which said plunger carries or said plungers carry the wire, the surface of said die at its upper edge being straight 10 and from that point having gradually formed on it a recess or recesses, into which the head of said plunger is or the heads of said plungers are adapted to fit, and between which and the head of said plunger or the heads of 15 said plungers the wire may be bent, and mechanism for ejecting the completed article, substantially as described.

9. In a machine for shaping wire, the combination of mechanism for feeding the wire, mechanism for cutting the wire and mechanism for shaping the wire consisting of one or more rotating forming plungers, adjustable vertically, and a forming die through which said plunger carries or said plungers 20 carry the wire, the surface of said die at its upper edge being straight and from that point having gradually formed on it a recess or recesses, into which the head of said plunger is or the heads of said plungers are adapted 25 to fit, and between which and the head of said plunger or the heads of said plungers, the wire may be bent, substantially as described.

10. In a machine for shaping wire, the combination of mechanism for feeding the wire, mechanism for cutting the wire and mechanism for shaping the wire consisting of one or more rotating forming plungers, adjustable vertically, and a forming die through 40 which said plunger carries or said plungers carry the wire, the surface of said die at its upper edge being straight and from that point having gradually formed on it a recess or recesses, into which the head of said 45 plunger is or the heads of said plungers are adapted to fit, and between which and the head of said plunger or the heads of said plungers, the wire may be bent, and mechanism for ejecting the completed article, substantially 50 as described.

11. In a machine for shaping wire, the combination of mechanism for feeding the wire, mechanism for cutting the wire and mechanism for shaping the wire consisting 55 of one or more rotating forming plungers, adapted for both vertical and rotary adjustment, and a forming die through which said plunger carries or said plungers carry the wire, the surface of said die at its upper edge 60 being straight and from that point having

gradually formed on it a recess or recesses, into which the head of said plunger is or the heads of said plungers are adapted to fit, and between which and the head of said plunger or the heads of said plungers, the 70 wire may be bent, substantially as described.

12. In a machine for shaping wire, the combination of mechanism for feeding the wire, mechanism for cutting the wire and mechanism for shaping the wire consisting 75 of one or more rotating forming plungers, adapted for both vertical and rotary adjustment, and a forming die through which said plunger carries or said plungers carry the wire, the surface of said die at its upper 80 edge being straight and from that point having gradually formed on it a recess or recesses, into which the head of said plunger is or the heads of said plungers are adapted to fit, and between which and the head of 85 said plunger or the heads of said plungers, the wire may be bent, and mechanism for ejecting the completed article, substantially as described.

13. In a machine for shaping wire, the 90 combination of mechanism for feeding the wire, mechanism for cutting the wire, mechanism for shaping the wire, consisting of one or more rotating forming plungers, and a forming die through which said plunger carries or said plungers carry the wire, and mechanism for ejecting the completed article, consisting of a reciprocating cam- 95 actuated pin passing through the head of each of said plungers, substantially as described.

14. In a machine for shaping wire, the combination of mechanism for feeding the wire, mechanism for cutting the wire, mechanism for shaping the wire, consisting of one 100 or more rotating forming plungers, and a forming die through which said plunger carries or said plungers carry the wire, and mechanism for ejecting the completed article, consisting of a reciprocating pin passing 105 through the head of each of said plungers, and actuated by a cam on said forming die, 110 substantially as described.

15. In a machine for shaping wire, the combination of mechanism for feeding the 115 wire, mechanism for cutting the wire, and mechanism for shaping the wire, consisting of a plurality of similar forming plungers arranged successively on a rotating wheel, and a forming die through which said plungers successively carry similar sections of the 120 wire, substantially as described.

16. In a machine for shaping wire, the combination of mechanism for feeding the wire, mechanism for cutting the wire, and mechanism for shaping the wire, consisting 125 of a plurality of similar forming plungers arranged successively on a rotating wheel, a forming die through which said plungers successively carry similar sections of the 130

wire, and mechanism for ejecting the completed article, substantially as described.

17. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adjustable vertically on said wheel, and a forming die through which said plungers successively carry similar sections of the wire, substantially as described.

18. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adjustable vertically on said wheel, a forming die through which said plungers successively carry similar sections of the wire, and mechanism for ejecting the completed article, substantially as described.

19. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adapted for both vertical and rotary adjustment, and a forming die through which said plungers successively carry similar sections of the wire, substantially as described.

20. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adapted for both vertical and rotary adjustment, a forming die through which said plungers successively carry similar sections of the wire, and mechanism for ejecting the completed article, substantially as described.

21. In a machine for shaping wire, the combination of mechanism for feeding the wire, mechanism for cutting the wire, and mechanism for shaping the wire, consisting of a plurality of similar forming plungers arranged successively on a rotating wheel, and a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, substantially as described.

22. In a machine for shaping wire, the combination of mechanism for feeding the

wire, mechanism for cutting the wire, and mechanism for shaping the wire, consisting of a plurality of similar forming plungers arranged successively on a rotating wheel, a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, and mechanism for ejecting the completed article, substantially as described.

23. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adjustable vertically on said wheel, and a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, substantially as described.

24. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adjustable vertically on said wheel, a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, substantially as described.

25. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adapted for both vertical and rotary adjustment, and a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, substantially as described.

26. In a machine for shaping wire, the combination of mechanism for feeding the wire, mechanism for cutting the wire, and mechanism for shaping the wire, consisting of a plurality of similar forming plungers arranged successively on a rotating wheel, each of said plungers being adapted for both vertical and rotary adjustment, a forming die through which said plungers carry successively similar sections of the wire, the surface of said die at its upper edge being straight and from that point having gradually formed on it a recess or recesses, into which the heads of said plungers are adapted to fit, and between which and the heads of said plungers the wire may be bent, and mechanism for ejecting the completed article, substantially as described.
27. In a machine for shaping wire, the combination of mechanism for feeding the wire, mechanism for cutting the wire, mechanism for shaping the wire, consisting of a plurality of similar forming plungers arranged successively on a rotating wheel, and a forming die through which said plungers carry successive sections of the wire, and mechanism for ejecting the completed article, consisting of a reciprocating cam-actuated pin passing through the head of each of said plungers, substantially as described.
28. In a machine for shaping wire, the combination of mechanism for feeding the wire, mechanism for cutting the wire, mechanism for shaping the wire, consisting of a plurality of similar forming plungers arranged successively on a rotating wheel, and a forming die through which said plungers carry successive sections of the wire, and mechanism for ejecting the completed article,
- consisting of a reciprocating pin passing through the head of each of said plungers and actuated by a cam on said forming die, substantially as described.
29. In a machine for shaping wire, the combination of mechanism for feeding the wire, mechanism for cutting the wire, mechanism for shaping the wire, consisting of a plurality of similar forming plungers arranged successively on a rotating wheel, and a forming die through which said plungers carry successive sections of the wire, the surface of said die at its upper edge being straight and from that point having gradually formed on it a recess or recesses, into which the heads of said plungers are adapted to fit, and between which and the heads of said plungers the wire may be bent, and mechanism for ejecting the completed article, consisting of a reciprocating pin passing through the head of each of said plungers and actuated by a cam on said forming die, substantially as described.
30. In a machine for shaping wire, mechanism for forming the wire consisting of two coöperating members, the surface of one of which at the point where the wire enters is straight and which from that point bears one or more recesses which increase in cross section as they recede from said point of entrance, and the other of which has one or more projections adapted to register with and pass through said recesses, substantially as described.
